LUBRICATING SYSTEM

Frederick C. Blanchard, Dorchester, Mass.

Application April 20, 1929, Serial No. 356,694

7 Claims. (Cl. 184—7)

This invention relates to automatic lubricating systems for application to industrial and other machines of various kinds, such as machine tools, wood-working machinery, rubber mills, 5 textile machinery, crushing and pulverizing mills, laundry machines, pumps, paper machinery, sugar mills and printing presses.

The invention will be best understood by reference to the following description, when taken 10 in connection with the accompanying drawings of one specific embodiment thereof, while its scope will be more particularly pointed out in the appended claims.

In the drawings:

15 Fig. 1 is an elevation, somewhat diagrammatic in character, of a lubricating system exemplifying the invention;

Figs. 2 and 3 are sectional views illustrating 20 in two positions one of the controlling valves of the system;

Figs. 4 and 5 are sectional views illustrating in two positions another of the controlling valves of the system;

25 Fig. 6 is a view, partly in elevation, and partly in section, illustrating the pump unit, the reservoir in which it is housed, and the motor and gearing for driving the pump unit;

Fig. 7 is a vertical, sectional view on an enlarged scale of one of the feeders of the system;

30 Fig. 8 is a sectional view on line 8—8 of Fig. 7;

Fig. 9 is a plan, partly in horizontal section, illustrating the pump unit of the system;

Fig. 10 is a sectional view, partly in elevation, 35 on line 10—10 of Fig. 9;

Fig. 11 is a sectional view, on the irregular line 11—11 of Fig. 10;

Fig. 12 is a sectional view on the line 12—12 of Fig. 10;

Fig. 13 is a sectional view on line 13—13 of 40 Fig. 10; and

Fig. 14 is a sectional view on line 14—14 of Fig. 10.

Referring to the drawings, and to the embodiment of the invention which is illustrated therein, and having reference at first to Fig. 6, there is shown a lubricating system comprising a tank 15, presenting a reservoir for oil. The tank is provided with a filler cap 16, seated on and about a curb 17, which prevents dirt from falling into 20 the oil when the cap is removed for the filling of the reservoir. A screen 18 is provided to prevent the entrance of foreign matter, and to filter the oil. The filler cap is conveniently mounted for movement to one side, by mounting 25 the same on a vertical pin or rod 19, which

extends loosely through a cover-plate 20, and is encircled by a spring 21, bearing at one end against the under side of the cover-plate and at its other end against a suitable abutment 22 secured to the rod. When the cover is lifted, 5 this spring yields, and after the cover is lifted clear of the curb, the cover may be swung laterally to uncover the screen. The cover-plate is conveniently secured to the tank by screws 23. A drain plug 24 near the bottom of the reservoir 10 is provided to drain the oil out of the latter, in case it should be necessary at any time.

Referring now to Fig. 1, leading from the reservoir is a conduit system comprising a plurality of sections of pipe 25, and one or more feeders 26, whose external forms vary somewhat to conform to the requirements of the particular situation where they are to be used. For example, the feeder may be a through feeder, designated by the additional character *a*, or a dead-end feeder, designated by the additional character *b*.

The feeder illustrated in Figs. 7 and 8 is one of the through feeders, which is interposed between and connects two pipe sections, and is coupled thereto by unions 27. The feeder comprises a body or casing 28, provided with a through passage 29 connecting the pipe sections, and providing for the passage of oil past this particular feeder. In the case of the dead-end feeder 26b, 30 the passage does not extend entirely through. Above the passage 29, there is a small, upwardly-directed opening 30, and a valve seat 31, and above the latter a chamber 32 for a needle valve 33, normally resting on the valve seat and closing the passage 30. The valve is suitably constructed and arranged to respond to a predetermined pressure in the system, as by being loaded with an appropriately arranged spring 34. Herein, the lower end of this spring rests 40 against an abutment 35, presented by the valve, and its upper end against an abutment 36, which is adjustable vertically by a hollow screw 37 threaded into the chamber 32. A steel ball 38, interposed between the abutment 36 and the 45 screw, is provided to ensure that the pressure of the spring shall be brought as nearly axial as possible with the valve. The rate of feed is increased by turning the screw in one direction, and is diminished by turning it in the other. 50 This varies the load of the spring imposed upon the needle valve.

When the valve opens, oil is admitted from the passage 29 into the chamber 32 thereabove, whence it descends by a lateral passage 39 (see 55

Fig. 8) to a nozzle 40. The rate of feed is readily observable through openings 41 in a casing 42, which is threaded onto the valve casing and holds a tubular glass 43. This casing presents 5 a nipple 44, to be screwed into an appropriate opening in or adjacent the bearing to be lubricated.

10 Into the inlet of the conduit system comprising the pipe sections 25 and feeders 26 oil is supplied under pulsating pressure by instrumentalities including a pressure-producing means such as a pumping unit (see Fig. 6) designated generally by the numeral 45, having a driving shaft 46 which extends through a bearing bushing 47 15 and a packing gland 48 to the exterior of the casing, where it is provided with a driving element, herein a gear 49 meshing with and driven by a pinion 50, to which power is furnished by appropriate means, herein an electric motor 51. 20 The pumping unit will now be described in detail, reference being had at first to Fig. 10. The principal part is a casting 52, which has a base 53 (see Fig. 14), secured to a pair of lugs 54, upstanding from the bottom of the tank. This 25 casting presents bearings 55 and 56 (see Fig. 10) for the shaft 46. It also presents a pair of pump cylinders 57, and a pair of piston valve cylinders 58. All of these cylinders are open at the top. The pump cylinders are closed at the bottom by 30 plugs 59, but the piston valve cylinders are open at the bottom to avoid the trapping of oil, which would prevent them from moving. Ports 60 connect the pump cylinders 57 with the piston valve cylinders 58. Inlet and outlet ports 61 and 62 are 35 interposed between and intersect the piston valve cylinders 58.

There are two pistons 63, one working in each cylinder, and there are two piston valves 64, one working in each piston valve cylinder. Each piston 40 valve is provided with a reduced portion 65, whose length and location with reference to the piston valve and its relationship with the several ports are such that, in the operation of the pump, oil is drawn into the port 61 and is discharged 45 through the outlet port 62. In the position of the parts shown in Fig. 10, the left-hand piston 63 is at the lowest point of its stroke, and is ready to start upwardly, while the right-hand piston is at the top of its stroke and is ready to 50 start in a downward direction, the left-hand piston valve is at mid-point on its upward stroke, and the right-hand piston valve is at mid-point on its downward stroke. Under these circumstances, the left-hand piston has been forcing 55 oil through the left-hand port 60 around the reduced portion of the left-hand piston valve and into the outlet port 62. Before the left-hand piston starts its up-stroke, and before the right-hand piston starts its down-stroke, the left-hand 60 piston valve rises, and the right-hand piston valve descends. When this happens, the reduced portion of the left-hand piston valve places the left-hand cylinder in communication with the inlet port 61, and the right-hand cylinder in 65 full communication with the outlet port 62. It follows that the next up-stroke of the left-hand piston causes oil to be drawn from the inlet port 61 into the left-hand cylinder, and oil to be forced from the right-hand cylinder into the outlet port 62.

The actuation of the pistons is conveniently accomplished by a pair of eccentrics 66 and a pair of eccentric straps 67, encircling the eccentrics and connected by pivots 68 to the pistons. Similarly, the piston valves are actuated by a pair of

eccentrics 69, encircled by eccentric straps 70, connected by pivots 71 to the piston valves. While all of the eccentrics might be secured to the shaft, if it were desired to operate the pump in only one direction, it is desirable that the 5 pump shall be capable of operation in either direction for convenience in connecting it to the motor, or other power means by which it is to be driven. For this reason, therefore, the eccentrics 69 are secured to a collar 72, which in turn 10 is secured to the driving shaft 46, but the eccentrics 66 are loosely mounted on the shaft, and are provided with pins 73 (one of which is well illustrated in Fig. 12), each of which is driven by a collar 74 secured to the shaft, and having 15 a lost motion driving connection with the pin, as by providing the collar with a slabbed-off portion 75, the extent of which is such that, if the direction of rotation of the collar be reversed, the collar will travel one-half a revolution before it 20 picks up the pin again. This arrangement ensures a proper timing of the pistons with relation to the piston valves, no matter which way the shaft is rotated.

Referring now to Fig. 14, the inlet of the pump 25 is provided with a strainer 76, mounted in a removable ring 77, which is threaded into an intake elbow 78, the latter in turn being threaded into the casing 52, and having a passage 79 communicating with the inlet port 61. The strainer 76 is located close to the bottom of the reservoir, and strains all the oil which enters the pump. An outlet pipe 80, threaded into the casting 52 and communicating with the outlet 30 port 62, is connected to the inlet of the first of 35 the pipe sections 25 of the conduit system.

Referring now to Fig. 6, there is also connected to the first pipe section of the conduit system a pipe 81, which extends in a downward direction through the cover-plate of the reservoir, and, as 40 shown in Fig. 13, is threaded into the casting 52, which is provided with a passage 82 communicating with said pipe and intersecting a passage 83, the latter having an outlet 84, adapted to by-pass 45 oil into the reservoir. When this outlet is open, so much of the oil is by-passed to the reservoir, that in the outlying piping system beyond the by-pass pipe 81, there is a comparatively low pressure (in practice about four pounds),—insufficient to make the feeders respond. When, 50 however, the by-pass outlet is closed, by pressure-controlling means such as a valve 85, the pressure in the system rises abruptly to a relatively high pressure (in practice about sixty 55 pounds), which is sufficient to make the feeders respond. As herein shown, the maximum pressure which is developed in the system when the valve 85 is closed is determined by a pressure relief valve presently to be described. In the 60 present example, the valve 85 is a slowly rotating plate, appropriately driven by and in synchronism with the pump, as by securing the valve by a pin 86 to a worm gear 87, which meshes with and is driven by a worm 88, suitably formed on or secured to the shaft 46.

Referring now to Fig. 11, the valve is maintained in firm engagement with the adjacent face of the casting 52, as by securing the valve and the worm gear by the pin 86 to a head 89 presented by a shaft 90, which turns in a bearing 91 presented by the casting, said shaft being constantly urged toward the right, as shown in Fig. 11, by a spring 92 which encircles the shaft and is interposed between a fixed abutment 93 on the shaft and a washer 94, which rests against 75

the adjacent face of the casting 52. This spring, therefore, constitutes an automatic take-up, which prevents leakage of the valve when the latter is closed.

5 In practice, the valve 85 is variously timed according to the requirements of the particular installation. In some cases, it is closed once in every sixty revolutions of the pump, and there are various ratios down to once in every seven 10 and one-half revolutions. When the valve is open, and oil is being by-passed back to the reservoir, the pressure in the piping system is only that required to keep the piping system filled. When the valve is closed, the oil is delivered 15 against a simple pressure relief valve now to be described, as a result of which there is produced in the system a comparatively high pressure for a brief interval of time, the pressure being of sufficient intensity to cause the feeders 20 to respond. If a pressure curve were taken, it would show comparatively long dwells of a pressure insufficient to open the feeders, and comparatively short periods of pressure sufficient to open the feeders.

25 Constantly operating, automatic systems feed altogether too much oil for many machines, thus resulting in wastage of oil and damage to goods. These disadvantages are avoided by the use of the herein-disclosed system, in which the operation 30 of the feeders is not only intermittent, but the feeding periods are "short kicks", separated by long dwells during which no oil is fed, thus giving more reliable feeds at much slower rates than is possible with feeders having a continuous delivery.

Referring to Fig. 13, there is provided a pressure relief valve designated generally by the numeral 95, the same comprising a casing 96 threaded into the casting 52, and having a passage 97 communicating with a short passage 98, which in turn communicates with the passage 83. The passage 97 terminates at its upper end in a valve seat 99, which is controlled by a valve 100 working in a cylindrical chamber 101. Above this valve, there is a comparatively stiff spring 102, whose lower end is seated in a chamber 103 provided in the upper end of the valve, and whose upper end rests against an abutment 104 presented by a plunger 105, which is guided by a cap 106 threaded onto the valve casing 96. A comparatively light spring 107 is interposed between the abutment 104, on the plunger, and an abutment 108 presented by the cap 106. A button 109 is attached to the upper end of the plunger. 55 When the mechanically actuated valve 85 closes the outlet 84 of the by-pass, and the pressure consequently rises, the valve 100 is lifted. Inasmuch as the spring 107 is lighter than the spring 102, the former yields to the greater extent under the influence of the pressure. The venting or relief of the valve is conveniently accomplished by providing the valve with a longitudinal passage 110, constantly communicating with the passage 97 and with one or more, herein 60 several radial passages 111 leading to a circumferential groove 112. The valve casing is provided with a relief port 113, shown in dotted lines in Fig. 13, and in full lines in Fig. 6. The inner end of this port is only slightly above the circumferential groove 112, and when the valve is lifted against the resistance presented by the springs 102 and 107, the groove registers with the port, and the pressure is relieved by the escape of oil through the relief port 113. A certain amount of oil leaks past the valve 100 into

the chamber 101 above the latter, and this chamber must be vented to prevent the accumulation of oil therein, which would interfere with the proper action of the valve. This venting is accomplished by two vent ports 114 (see Figs. 9 5 and 10).

Referring again to Fig. 13, the button 109 furnishes a visual indication of the integrity of the system, because it rises and falls with the pressure pulsations. If the oil supply were exhausted, or if the pump were not functioning or developing proper pressure, the button would not rise and fall. Similarly, if the oil line were broken, badly leaking or clogged, the button would remain dormant. This feature is of great 15 practical value, because the operator of the machine, or the cillwright, need only glance at the button to be assured as to the lubrication of the machine.

In practice, the button is marked with the word 20 "Flush". By depressing the button, the heavy spring 102 is compressed, thereby loading the relief valve heavily, so that the pulsation-pressure is greatly increased, with a corresponding increase in the amount of oil fed to all the bearings. 25 This simultaneous flushing is advantageous when starting a machine which has been idle for some time, or if exceptionally difficult operating conditions must be met. When the button is released, the pressure is automatically restored to 30 normal, and the established feed rates are resumed.

Referring now to Fig. 1, the system is applied to a plurality of machines 115, each having a plurality of bearings 116, each one fed by one 35 of the feeders 26. One of these machines is designated by the additional character A, and another by the additional character B. The machine 115A has its feeders connected in series by pipe connections which, together with the 40 feeders, constitute a branch leading from the main line or conduit, and this branch terminates in a dead-end feeder 26b. The machine 115B has its feeders connected in series by two branches, having a common connection leading 45 from the main conduit, and each of these two branches terminates in a dead-end feeder 26b. Each of the remaining machines 115 has its feeders connected in series by pipe connections which, together with the feeders, constitute a 50 local auxiliary loop leading from and back to the main conduit.

Referring now to Figs. 2 and 3, each loop may be connected to and disconnected from the main conduit by appropriate valve means, herein a 55 four-way valve 117 comprising a stator 118 and a rotor 119. The stator is provided with four ports 120, and the rotor is provided with two passages 121. As shown in Fig. 2, the stator is in the position in which the loop is in communication with, and for the time being virtually a 60 part of, the main conduit, in the sense that the entire column of oil flowing through the main conduit flows through the loop also. When the rotor is in the position shown in Fig. 3, the loop 65 is disconnected from the main conduit, and the column of oil in the main conduit flows past the loop without entering it. Referring now to Figs. 4 and 5, the branches associated with the machines 115A and 115B may be connected to 70 and disconnected from the main conduit by appropriate valve means, herein a three-way valve 122, comprising a stator 123 and a rotor 124. The stator is provided with three ports 125, and the rotor is provided with a passage 126. As 75

shown in Fig. 4, the stator is in the position in which the branch is in communication with the main conduit, and part of the column of oil flowing in the latter is taken off into the branch. 5 When the rotor is in the position shown in Fig. 5, the branch is disconnected from the main conduit, and the column of oil in the latter flows past the branch without any oil entering the latter.

Each machine is provided with an appropriate 10 power-controlling means for starting and stopping the same. In the example shown, the power-controlling means comprises tight and loose pulleys 127 and 128 on a driving shaft 129, a belt 130, and a belt shifter comprising a fork 131 and 15 a sliding rod 132, provided with a handle 133. When the belt is engaged with the tight pulley, as shown, the machine is driven, and when the belt is engaged with the loose pulley, the machine is stopped.

20 The control of the machine is conveniently co-ordinated with the control of its valve by providing the latter with an arm 134, connected by a link 135 to the rod 132, the arrangement being such that when the machine is running, the valve 25 is in the proper position to cause oil to be supplied to the feeders associated with the machine. When, however, the machine is stopped, the supply of oil is shut off by the valve. Thus it is evident that the operator of the machine need not 30 give any thought to the lubrication of the machine, except to inspect the sight feed, and even this inspection may be assigned to one person, such as a department oilwright in charge of the entire system. As shown in Fig. 1, the main conduit, comprising the conduit sections 25, extends 35 from the reservoir past the several machines in succession, and terminates beyond the last, or most outlying machine (the one at the upper left-hand portion of Fig. 1) in a dead-end, which 40 may be closed by a cap or plug 136, which may be removed to scavenge the system of air when first starting a new installation, or to allow the system to be flushed out, if desired.

The general operation of the system should be 45 evident without further description. The pump, driven by the motor, is continued in operation during working hours, and delivers fresh oil to the system in sufficient quantity to satisfy the demand of all the feeders. Each feeder, adjusted to 50 the number of drops per hour called for by the bearing which it serves, can be checked in an instant by the department oilwright, or by the machine operator examining the sight-feed. The person in charge knows that each system under 55 his care is functioning as a whole, because he sees the indicating and flushing plunger reciprocate. When the machine is running, the system delivers oil in predetermined amounts to each bearing, the amount to each of course being predetermined 60 by adjustment of the spring-loading screw 37. When any machine is idle, no oil is delivered to it. The use of the system is characterized by economy of oil. By accurate and independent adjustment of the feed rod at each lubrication 65 point, from two to three drops per hour to substantially a stream, it is possible to deliver a minimum amount of oil consistent with safety. The system provides against waste, as well as against excess of oil.

70 The quick pressure impulse of high intensity and the resulting jump of the needle of each feeder produce a measurable feed of short duration, taken from a circulating supply of lubricant. This makes possible much lower feed rates than 75 heretofore regarded as safe. The jump of the

feeder needle overcomes any tendency of the oil to form a film in the valve seat. This opening, being above the column of oil, safe-guards it from the entrance of foreign matter, which might be in the system.

Reference is made to my co-pending applications, Serial No. 338,546, filed February 8, 1929 (now Patent No. 1,900,754), and Serial No. 338,549, filed February 8, 1929 (now Patent No. 1,953,824). In each there is shown a circulatory system having a conduit extending from a pressure-producing unit past one or more machines, each provided with one or more feeders supplied by the conduit, and the latter conducts the surplus oil back to the source. In each patent a valve at 10 the return end of the conduit causes a pulsating pressure which in turn causes intermittent operation of the feeder or feeders. In the present application, the valve which causes the pulsations is at the inlet end of the system.

Having thus described one embodiment of the invention, but without limiting myself thereto, what I claim and desire by Letters Patent to secure is:

1. The combination of a machine having controlling means to start and stop the same, one or more oil feeders for feeding oil to said machine, a feeder-supplying conduit, means for supplying to the inlet of said conduit oil under pulsating pressure which causes said feeder or feeders to respond when it rises to a predetermined point, and means connected to said controlling means to cause stopping of said machine to be accompanied by cessation of the supply of oil to said machine.

2. The combination of a machine having controlling means to start and stop the same, one or more oil feeders for feeding oil to said machine, a feeder-supplying conduit, means for supplying to the inlet of said conduit oil under pulsating 30 pressure which causes said feeder or feeders to respond when it rises to a predetermined point, a valve controlling the supply of oil from said conduit to said feeder or feeders, and means for coordinating the operation of said controlling 35 means and said valve to cause stopping of said machine to be accompanied by closing of said valve and to cause starting of said machine to be accompanied by opening of said valve.

3. In a lubricating system, the combination of 50 a reservoir, a main conduit to which oil is supplied under pressure from said reservoir, said conduit having an outlying dead-end, a loop conduit between said reservoir and said dead-end, one or more feeders supplied by said loop conduit, 55 and means at will to constitute said loop conduit a part of said main conduit.

4. In a lubricating system, the combination of 60 a reservoir, a main conduit having an inlet from said reservoir and having an outlying dead-end, 65 a loop conduit between said inlet and said dead-end, one or more pressure-responsive feeders supplied by said loop conduit, means at will to constitute said loop conduit a part of said main conduit, and means for supplying oil from said reservoir to said inlet under pulsating pressure which causes said feeder or feeders to respond when said loop conduit is in communication with said main conduit.

5. In a lubricating system, the combination of 70 a reservoir, a main conduit having an inlet from said reservoir and having an outlying dead-end, a branch conduit between said inlet and said dead-end, one or more pressure-responsive feed- 75

ers supplied by said branch conduit, means at will to place said branch conduit in communication with said main conduit, and definitely-timed, power-operated, means for supplying oil from 5 said reservoir to said inlet under predetermined pulsating pressure which causes said feeder or feeders to respond when said branch conduit is in communication with said main conduit.

6. The combination of a machine having starting means to start the same, one or more feeders 10 for feeding oil to said machine, a feeder-supplying conduit, means for supplying to the inlet of said conduit oil under pulsating pressure which causes said feeders to respond and to feed when 15 the pressure rises to a predetermined point, and means connected to said starting means to cause

oil to be supplied to said machine when the latter is started.

7. The combination of a machine having controlling means to start and stop the same, one or more feeders for feeding oil to said machine, a feeder-supplying conduit, means for supplying to the inlet of said conduit oil under pulsating pressure which causes said feeders to respond and to feed when the pressure rises to a predetermined point, and means connected to said controlling 10 means to cause oil to be supplied to said machine contemporaneously with the starting of said machine and to cause the supply of oil to be discontinued contemporaneously with the stopping of said machine. 15

FREDERICK C. BLANCHARD.
